UNITED STATES PATENT OFFICE.

LÉON BÉDARD, OF QUEBEC, QUEBEC, CANADA.

GAS-COCK.

1,018,350.

Specification of Letters Patent. Patented Feb. 20, 1912.

Application filed May 23, 1911. Serial No. 629,042.

To all whom it may concern:

Be it known that I, LÉON BÉDARD, a subject of the King of Great Britain, residing at Quebec city, in the Province of Quebec, Canada, have invented new and useful Improvements in Gas-Cocks, of which the following is a specification.

This invention relates to gas cocks, the object of the invention being to provide a simple and effective device which will automatically lock the cock when closed, and which will require a manual operation to unlock the same before the gas can pass through the cock.

With the above object in view, and others which will appear as the nature of the invention progresses, the improvement resides in the novel construction and arrangement of parts hereinafter fully described and claimed.

In the drawings, accompanying this specification, there has been illustrated a simple and preferred embodiment of the improvement, it being understood, however, that the showing therein is merely illustrative and that changes in the minor details of construction, such as size, shape, proportion, etc., which fall within the scope of the appended claim, may be made, if desired.

In the drawings,—Figure 1 is an elevation of a cock constructed in accordance with the present invention. Fig. 2 is a vertical transverse sectional view taken upon the line 2—2 of Fig. 1. Fig. 3 is a horizontal sectional view taken upon the line 3—3 of Fig. 1.

The gas cock is primarily adapted for use in connection with gas stoves, but, of course, is susceptible for use in connection with illuminating gas burners. In the drawings, the numeral 1 designates the body or casing of the cock. This body 1 has integrally connected thereto a threaded inlet port 2 and an outlet port 3. The port 3 may be provided with a suitable burner if desired, and the said burner may have a flame adjusting cap. The casing 1 is formed with the usual threaded bore which is arranged transversely of the inlet and outlet ports 2 and 3, and which of course communicates with the said ports. The top of the casing has a suitable recess 4 arranged adjacent one of its faces, the said recess being adapted for the reception of a pin 5 provided upon the tapering plug 6 of what may be termed the valve proper. The off-

sets or shoulders provided by the said recess are adapted to limit the movement of the valve so as to bring its port 7 into register with the ports 2 and 3 when the gas is to be turned on and so as to limit the movement of the said plug in an opposite direction when the flow of gas is to be turned off. The plug 6 is provided with the usual operating handle 8, and the said plug is further provided with a vertically arranged slot 9. This slot 9 has its inner wall preferably beveled or inclined from the top to the bottom of the said slot, and the slot is arranged at an angle with relation to the pin 5.

The numeral 9' designates the automatic locking member for the cock. This member 9' comprises an elongated body portion 10 having a head 11 and having its inner face adjacent its upper portion provided with the spring 12, the latter adapted to be received within a suitable recess formed in the upper portion of the inner wall of the slot 9. The spring 12 is adapted to exert an outward pressure upon the body 10, and the lower portion of the said body is provided with a reduced extension 14. This portion 14 is adapted to receive a lock bar 15, the latter projecting beyond each of the faces of the body 10. The tapering plug is provided with a depression 16 which is adapted to receive the inner portion of the lock bar 15, and the outer portion of the said lock bar is adapted to engage with the shoulder provided by the recess formed upon the casing opposite to that engaged by the pin 5 when the plug is turned so as to prevent the passage of gas therethrough. When the cock is to be opened to allow the passage of gas therefrom, a pressure is exerted upon the head 11 of the lock, thus forcing the lock bar rearwardly within the slot 9 so that the projecting portion of the lock bar is free of the said shoulder and the handle 8 may be rotated without further interference of the said lock bar until the same is stopped by the pin 5 contacting the shoulder of the recess previously contacted by the projecting portion of the lock bar. When the gas is to be turned off no attention will be paid to the lock 9, as the lock bar of the same will automatically spring into position after the pin 5 contacts with the opposite shoulder formed by the recess.

The advantages of the arrangement as disclosed is apparent from the fact that

with my device it is impossible to accidentally open the gas cock, a contingency that frequently occurs in cocks generally used upon gas stoves of the modern construction, 5 and that only a slight manual operation is required to operate the lock 9, the mere pressure upon the head of the same causing the lock 15 to slide against the wall adjacent the recess of the casing when the cock is to 10 be opened. The automatic lock is preferably arranged adjacent the gas stoves, so that the same will be arranged out of the sight of persons not acquainted with the operation of the cock, and this materially 15 adds to the safety of such devices.

Having thus fully described the said invention, what I claim is:—

A stop cock including a casing having the usual ports and a tapering bore communicating with the ports, a tapering plug having 20 an opening communicating with the ports, a pin upon the plug, the casing having the usual recess forming the oppositely arranged shoulders, an automatic lock, the plug being 25 provided with a slot having its inner wall

inclined for the reception of the lock, the said plug being provided with a recess and with a depression, the lock having its upper extremity provided with a spring engaging within the recess, the lower extremity 30 of the lock having a lock bar projecting beyond each of the faces thereof, one of said projecting portions engaging within the depression of the plug, the projecting portion of the lock bar adapted to engage the 35 shoulder of the recess of the casing opposite to that occupied by the pin of the plug when the cock is in the closed position, the lock being provided with a head projecting beyond the plug, and said head adapted 40 to be contacted to force the plug within the recess and the lock bar out of engagement with the shoulder when the said plug is to be rotated to open the cock.

In testimony whereof I affix my signature 45 in presence of two witnesses.

LÉON BÉDARD.
